UNITED STATES PATENT OFFICE.

JACOB B. WHITE, OF COLUMBUS, OHIO.

BEDSPRING BRACE.

Application filed May 6, 1926. Serial No. 107,283.

This invention is specifically directed to improvements in bed springs of the type embodying a rigid lower frame and a flexible upper frame, and wherein the frames are resiliently separated by a multiplicity of coiled springs arranged between the frames, and it is an object of the present invention to provide an improved brace construction between the frames of a bed spring of this type for the purpose of stabilizing relative movement between said frames so as to limit such movement to travel in substantially vertical planes to preclude undue lateral sway thereof and, also, to preserve at all times the proper shape and appearance of the bed spring.

With these and other objects in view, as will appear as the description proceeds, the invention consists in the novel features of construction, combinations of elements and arrangements of parts hereinafter to be fully described and pointed out in the appended claims.

In the accompanying drawing:

Figure 1 is a plan view,
25 Figure 2 is a vertical sectional view on the line 2—2 of Figure 1,

Figure 3 is a transverse sectional view on the line 3—3 of Figure 2.

Referring more particularly to the drawing the numeral 1 designates the lower rigid frame of the bed spring. This frame is composed, as usual, of a plurality of angle bars rigidly connected to constitute a rectangular plane, and connected with the angle bars are a plurality of longitudinally spaced transversely extending cross members 2, rigidly connected at their ends to the frame 1. This frame constitutes a base for the reception of the lower end of a plurality of spirally coiled springs 3, which springs are arranged so that their convolutions of largest diameter are arranged in the upper ends thereof and their convolutions of smallest diameter disposed to rest upon and are secured to the frame 1 and its cross members 2. The upper end of the springs 3 may also be connected by means of a plurality of short, horizontally extending and diagonally disposed coil springs 4, which serve to hold the main springs 3 in position and also add to the general resiliency, as usual, of the bed spring. Connected in any suitable manner with the outermost of the springs 3 is a flexible frame or border wire 5, which surrounds the margins of the upper portions of the bed springs and is employed to retain the shape of the latter.

In order to stabilize the operation of the bed springs and to confine the upper flexible frame for movement in a vertical plane, the present invention contemplates the provision of an improved base construction consisting of a pair of cooperating units connected preferably with the central portion of the longitudinally extending angle bars of the frame 1 and arranged generally transversely of the frame. Each of these braces is formed to comprise an angle bracket 6, arranged transversely of the frame 1 and having its outer end recessed as at 7 so that the upper horizontal leg of the bracket may be riveted or otherwise secured to the frame 1. The bracket 6 of each brace extends inwardly a relatively limited distance and has pivotally secured to the vertical legs thereof as at 8 at the extreme inner end of said bracket a check link 9, which extends diagonally upwardly and has its upper or outer end pivotally secured as at 10 to an upwardly and inwardly extending link 11. The upper end of this link is pivoted as at 12 to a diagonally extending arm 13, which has its upper end hooked as at 14 for engagement with the border wire 5. The arm 13 extends inwardly and downwardly with respect to the spring and has its lower end pivoted as at 15 to the floating link 16 which, in turn, intersects the link 9 and is pivoted to the latter as at 17. The extreme lower end of the link 16 is provided with a laterally projecting stud 18, which is received within an elongated slot 19 provided in the fixed bracket 6.

From the foregoing it will be seen that a brace construction is provided wherein the upper or hook shaped end 14 of the arm 13 is limited for travel in a substantially vertical line irrespectively of the relative spacing which exists between the upper and lower frame of the spring. This construction, therefore, serves to prevent lateral swaying of the spring assembly 4 and limits the travel of said assembly to vertical planes. The slot 19 serves to definitely limit the upward movement of the brace so as to relieve the spring assembly of strain when the bed spring is lifted bodily by forces applied to the border wire 5. Again, the hook 14 serves to securely confine the border wire to a determined position and prevents the latter from twisting or bending under the influence of the springs 3 and 4 or to other pressures which are directed outwardly and laterally. The brace is of simple and positive construction, does

not interfere with the normal resiliency of the bed spring and effectively serves to protect the latter when unusual forces are applied thereto.

5 5. What is claimed is:

1. In a bed spring, a rigid lower frame, a spaced upper frame, springs interposed between said frames for resiliently spacing the latter, a transversely extending bracket rigidly connected with said lower frame, a pair of cross links, pivoted to each other at a point intermediate the length, one of said links having the lower end thereof connected by a fixed pivot with said bracket, the other

10 10. idly connected with said lower frame, a pair of cross links, pivoted to each other at a point intermediate the length, one of said links having the lower end thereof connected by a fixed pivot with said bracket, the other

15 15. of said links having its lower end connected with said bracket by a pin and slot connection, an upwardly and angularly extending arm having the upper end thereof engaged with said upper frame, the lower end of said

20 20. arm being pivotally connected with the upper end of the link having the pin and slot connection with said bracket, and a relatively short link connection between an intermediate part of the length of said arm and the upper

25 25. end of the link having the fixed pivot connection with said bracket.

2. In a bed spring, in combination, a base frame, and a resiliently spaced upper frame having a border element, an arm having the

30 30. upper end thereof connected with said border element and extending downwardly and inwardly therefrom, a check link having the lower end thereof pivotally connected with said lower frame and arranged to extend

35 35. parallel to said arm, a floating link pivotally connected with the intermediate point of said check link and having the upper end thereof pivotally connected with the inner end of said arm, the lower ends of said floating link having a pin and slot connection with said lower frame, and a short link section connected pivotally with the upper end of said check link and with an intermediate

40 40. part of said arm.

45 45. 3. In a bed spring, in combination, a rigid

base frame, an upper frame resiliently spaced from said base frame and including a flexible border element, an arm having the upper end thereof connected with said border element and extending inwardly and downwardly 50 therefrom, a stationary bracket extending inwardly and laterally from the base frame, a check link arranged in parallel relationship with respect to said arm and having the lower end thereof pivotally connected with said 55 brackets, a second link crossing said check link and pivotally connected therewith, the upper end of said second link being pivotally connected with the lower end of said arm and having its lower end provided with a pin 60 and slot connection with said bracket, and a third link having the lower end thereof pivotally connected with the upper end of said check link and its upper end pivotally connected with a point intermediate of the 65 length of said arm.

4. In a bed spring, in combination, a rigid base frame, an upper frame resiliently spaced from said base frame and including a flexible border element, a brace arm arranged within 70 the confines of said spring and having the upper end thereof connected with said border element, a rigid transverse support on said base frame, and a pair of crossed links 75 pivoted to each other approximately midway of their length, one of said links having its lower end pivotally connected to the inner end of said transverse support, the other of said links having its lower end connected with said support by a pin and slot connection, and its upper end to the end of said brace arm, and a third link pivotally connected to the brace arm and to the upper end of the first named cross link, the third link being arranged in parallel relationship 80 with respect to the link having the pin and slot connection.

In testimony whereof I affix my signature.

JACOB B. WHITE.
